(57) **CLAIM**

The ornamental design for a portable monitor, as shown and described.

DESCRIPTION

FIG. 1 is a front, top and right side perspective view of a portable monitor, showing our new design;

FIG. 2 is a rear, bottom and left side perspective view thereof;

FIG. 3 is a rear, top and right side perspective view with the stand in an open configuration of use thereof;

FIG. 4 is a rear, top, and left side perspective view with the stand in another open configuration of use thereof;

FIG. 5 is a front view thereof;

FIG. 6 is a rear view thereof;

FIG. 7 is a left side thereof;

FIG. 8 is a right side view thereof;

FIG. 9 is a top plan view thereof; and,

FIG. 10 is a bottom plan view thereof.

The broken lines shown in the drawings illustrate portions of the portable monitor that form no part of the claimed design.

1 Claim, 10 Drawing Sheets
